CLAIM

The ornamental design for an office alcove workspace, as shown and described.

DESCRIPTION

FIG. 1 is an upper, front, left perspective view of a first embodiment of an office alcove workspace showing the

office alcove workspace door in an open position and configured with exemplary transparent upper side wall panels and opaque lower side wall panels.

FIG. 2 is left-side elevation view of the office alcove workspace of FIG. 1.

FIG. 3 is rear elevation view of the office alcove workspace of FIG. 1.

FIG. 4 is a right-side elevation view of the office alcove workspace of FIG. 1.

FIG. 5 is a front elevation view of the office alcove workspace of FIG. 1.

FIG. 6 is a top view of the office alcove workspace of FIG. 1.

FIG. 7 is an upper, front, left perspective view of the office alcove workspace of FIG. 1 showing the office alcove workspace door in an alternate closed position.

FIG. 8 is a left-side elevation view of a second embodiment of the office alcove workspace of FIG. 1 alternately showing the left side wall configured with transparent upper and lower side wall panels. A right-side elevation view of the second embodiment of the office alcove workspace is a mirror image of FIG. 8 and is not separately illustrated.

FIG. 9 is a left-side elevation view of a third embodiment of the office alcove workspace of FIG. 1 alternately showing the left side wall configured with opaque upper and lower side wall panels. A right-side elevation view of the third embodiment of the office alcove workspace is a mirror image of FIG. 9 and is not separately illustrated.

FIG. 10 is an upper, front, right perspective view of an alternate fourth embodiment of the office alcove workspace which is a mirror image of FIG. 1. FIG. 10 showing the office alcove workspace configured for the workspace entrance/exit door opening to be adjacent the right side wall and the door shown in an open position; and,

FIG. 11 is an upper, front, right perspective view of the office alcove workspace of FIG. 10 showing the office alcove workspace door in an alternate closed position which is a mirror image of the office alcove workspace of FIG. 7.

The ornamental design which is claimed is shown in solid lines in the drawings. The broken lines in the drawings form no part of the claimed design. Broken lines formed by equal length dashes (i.e., dash-dash) show unclaimed portions of the design. Broken lines formed of unequal length dashes (i.e., dash-dot) at the outer ends of individual components having a jagged element show boundaries between claimed and unclaimed portions of the design. Illustrated features of the ornamental design include a symbolic break in the
